LAWRENCE Y. SPEAR, OF NEW LONDON, CONNECTICUT, ASSIGNOR TO ELECTRIC BOAT COMPANY, OF NEW YORK, N. Y., A CORPORATION OF NEW JERSEY.

INTERNAL-COMBUSTION ENGINE.

Application filed February 8, 1924. Serial No. 691,420.

To all whom it may concern:

Be it known that I, LAWRENCE Y. SPEAR, a citizen of the United States, residing at New London, in the county of New London, State of Connecticut, have invented certain new and useful Improvements in Internal-Combustion Engines; and I do hereby declare the following to be a full, clear, and exact description of the invention, such as 10 will enable others skilled in the art to which it appertains, to make and use the same.

This invention relates to a fuel injection device for use in double acting internal combustion engines of the Diesel type, and the 15 principles of the invention may be utilized in such engines which work either on the two or four stroke cycle. More specifically, the invention provides a fuel injection device particularly adapted for injecting fuel into 20 that part of the cylinder of a double acting engine defined by the piston and by the head through which the piston rod passes.

In engines of the type above generally referred to the piston rod to which the piston 25 is connected passes through one head of the cylinder. This head may be separate from the cylinder or may be cast integral therewith, but in either case the head has a passage of considerable length formed in it 30 through which the piston rod moves. The piston rod is packed by means of packing which lies in this passage, and for this purpose there is ordinarily employed a cylindrical sleeve or box which fits the piston rod 35 closely at one end of the passage, and has a portion of greater diameter in which the packing lies. The packing which is of any well-known type is held in place in the box by means of a gland and sometimes a second 40 gland is employed to hold in place further packing which lies against the inner face of the first gland. In such an engine oil is injected into the cylinder both above and below the piston so as to produce impulses in 45 either direction. The oil is injected by means of mechanical timing apparatus and in the upper cylinder head there is a nozzle or nozzles through which the oil is sprayed into the cylinder. These may be placed at 50 any convenient point in the upper end of the cylinder and there are comparatively few difficulties in designing a satisfactory injection device for this portion of the cylinder. The problem of injecting fuel into

the lower end of the cylinder, however, is 55 considerably complicated by reason of the space occupied by the piston rod and the necessity of having a passage through the cylinder head in which this rod may move. It is necessary that these spraying nozzles or 60 nozzle should not discharge against the surface of the piston rod, and it is quite difficult to inject the fuel into the annular space so that it will intimately mix with the air necessary for its combustion. 65

Heretofore sprayers have been fitted in cannons connecting the inner and outer walls of the lower head and spraying substantially in the direction of the movement of the piston, or by cannons connecting the walls 70 of the cylinder jacket and liner substantially at right angles to the direction of motion of piston.

In order to allow fuel to meet the air required for combustion, sometimes two or 75 more approximately vertical sprayers are fitted in the cylinder head, or two or more approximately horizontal sprayers are fitted in the cylinder wall more or less tangentially so as to avoid injecting fuel directly against 80 the piston rod. In the case of the first construction mentioned, the sprayer cannons increase the difficulties of cooling the head and result in a complicated casting ill-adapted to resist the stresses, including heat stresses, 85 to which it is subjected in service. In the case of the second construction mentioned, the cannon necessarily forms a rigid connection between the liner or wall of the cylinder proper and the water jacket. Owing 90 to the differences involved in thicknesses, masses of metal and temperatures, such constructions are likely to develop destructive stresses in service. 95

The present injection system is intended to avoid the disadvantages above referred to and it involves the use of the box encasing the packing as a means for supporting the spraying nozzles and supplying fuel thereto. In one form of the invention this box 100 is drilled suitably so as to form a plurality of passages preferably spaced equidistantly about the circumference of the box. Mounted on the upper end of the box, which will ordinarily lie approximately flush with 105 the inner face of the cylinder head, are nozzles which extend into the cylinder a slight distance. Each nozzle is in communication

with one of the oil passages formed in the box and fuel supply pipes are connected to the passages beyond the end of the water jacket where the box is exposed. The nozzles are arranged with their spraying orifices directed inwardly and toward the cylinder wall so that the oil is directed away from the piston rod and into the combustion space. With this arrangement it will be seen that no cannons need be used between the inner and outer walls of the cylinder head specially for the injection device. The cylinder head may be cast integrally with the cylinder wall, or else may be formed separately therefrom in the usual way, but in either case the head may be symmetrical and the cooling of the head is greatly simplified since a much greater proportion of the head surface may be exposed to the cooling medium. Ordinarily the box will be found to be of sufficient size to permit the necessary drilling for the oil passages, but if this is not the case when the cylinder head is formed the passage through it in which the piston rod moves will be made sufficiently large so that a sufficiently large box may be employed.

In the accompanying drawings I have illustrated the invention in that form which is now preferred, and in these drawings, Fig. 1 is a vertical sectional view of the lower head of a double acting internal combustion engine with the new type of box in place,

Fig. 2 is a transverse sectional view on the line 2—2 of Fig. 1,

Figs. 3 and 4 are small scale, longitudinal, sectional views of double acting engines of the prior art, Fig. 3 showing the valve cannons placed horizontally, and Fig. 4 the cannons placed vertically.

Referring now to these drawings, the engine is seen to consist of a cylinder 5 here shown provided with a lower cylinder head 6 which is cast integral with the cylinder wall. This head is formed with an extension 7 providing a passage through which the piston rod 8 moves. The piston rod has mounted upon it the piston 9, which lies within the cylinder. The cylinder and lower head are encased in a water jacket 10 which forms annular water spaces 11 and 12 around the cylinder and the cylinder head. The space 12 permits the cooling of the passage 7. A sleeve or box 13 lies within the extension 7 and has a portion 14 which fits the piston rod closely. This portion lies adjacent the piston. The box has another portion 15 of increased diameter in which lies the packing 16 of any well-known type. The box terminates at its outer end in a lateral flange 17 which lies beyond the end of the water jacket and a gland 18 fitting tightly around the piston rod holds the packing in place. The gland 18 also has a recess in which is placed packing 19 which is, in turn,

held in place by a second gland 20. The box at its inner end lies substantially flush with the inner face of the cylinder head 6.

The portion 14 of the box is drilled to form oil passages 21 and spray nozzles 22 are mounted in the end of the box so as to extend a slight distance into the cylinder. These nozzles are in communication with the passages 21 and in this particular instance there are shown four passages and four nozzles. At the point 23 where the box has a shoulder by reason of its having a portion of increased diameter there is drilled a passage 24 communicating with the passage 21. The outer end of this inclined passage 24 is closed by a plug 25. A longitudinal passage 26 is drilled through the sleeve, its lower, outer end being closed by a plug 27. This passage 26 communicates with the inclined passage 24. An inclined passage 28 is then drilled through the lateral flange of the box to communicate with the longitudinal passage 26 and a fuel supply pipe 29 is connected to this passage 28 by a suitable coupling 30 which threads into the flange. A similar construction is employed for each of the passages, and while the box here illustrated has been shown with four such passages, a greater or less number may be used as may be required.

The fuel supply pipes are supplied with oil which is injected at timed intervals and this oil is sprayed into the cylinder through the nozzle. These nozzles, as here shown, discharge this oil upwardly into the cylinder, distributing it evenly in the combustion space.

In Fig. 3 the old type of engine has been illustrated to show the manner in which the oil is injected. Passage 32 is formed through a cannon which connects the cylinder wall and the water jacket. A number of these passages are ordinarily used and in making the cylinder it is necessary to provide such a cannon for each passage. It will be seen that the casting of the cylinder is considerably complicated by the necessity of forming the cannons between the cylinder walls and the jacket and this distribution of the metal produces detrimental effects, not only by reason of its interference with the circulation of the cooling medium, but also by reason of unequal expansion of the different parts in casting, as well as when the engine is in operation.

In Fig. 4 there is shown an engine of the prior art. In this view the lower cylinder head is shown as being cast integral with the cylinder jacket and oil is introduced into the cylinder through passages 33. These passages extend substantially in the direction of the cylinder axis and it will be seen that in order to provide for these oil passages the cylinder cover is so formed that it cannot be thoroughly cooled throughout all

- of its surface. Furthermore, the cover is formed of large masses of metal so that the expansion and contraction difficulties are greatly increased. Since the passages are formed in the metal of the cover itself, it follows that the cover must have a certain minimum diameter in order to permit of the mounting of the spray nozzles within it while maintaining the required strength.
- 10 Consequently, engines of this type cannot be made of as small bore as is possible when the packing box is used for the oil passages. Also on both the engines illustrated in Figs. 3 and 4 the cylinder covers cannot be made wholly symmetrical either when cast as part of the cylinder and jacket, or when cast separately therefrom. This lack of symmetry results in difficulties in operation due to cracking. With the engine shown in Fig. 20 these difficulties are eliminated.
- It will be observed, furthermore, that with the engine constructed in accordance with my invention not only is the making of the various parts of the engine considerably simplified and its life lengthened, but the assembly of the injection apparatus is much simpler and it may be easily dismantled should occasion arise.
- I claim:
- 30 1. In an internal combustion engine the combination of a cylinder, a piston in the cylinder, a head in the cylinder having a passage therethrough, a piston rod connected to the piston and movable in the passage, a box in the passage fitting about said piston rod the inner end of this box terminating substantially flush with the inner wall of the cylinder head, and a plurality of oil supply passages in said box.
- 40 2. In an internal combustion engine the combination of a cylinder, a piston in the cylinder, a head in the cylinder having a passage therethrough, a piston rod connected to the piston and movable in the passage, a box in the passage containing packing fitting said piston rod the inner end of this box terminating substantially flush with the inner wall of the cylinder head, and a plurality of spaced oil passages through said box.
- 50 3. In an internal combustion engine, the combination of a cylinder, a piston in the cylinder, a head in the cylinder having a passage therethrough, a piston rod connected to the piston and movable in the passage, a box in the passage fitting said piston rod, a plurality of oil passages in said box, and nozzles mounted in the box in communication with said passages and having orifices for discharging oil into the cylinder.
4. In an internal combustion engine, the combination of a cylinder, a piston in the cylinder, a head in the cylinder having a passage therethrough, a piston rod connected
- 55 to the piston and movable in the passage, a box in the passage fitting said piston rod the inner end of this box terminating substantially flush with the inner wall of the cylinder head, a plurality of oil passages 70 through the box, and means mounted in the box and connected with each oil passage for distributing oil uniformly in the combustion space.
5. In an internal combustion engine, the 75 combination of a cylinder, a piston in the cylinder, a head in the cylinder having a passage therethrough, a piston rod connected to the piston and movable in the passage, a box in the passage fitting said 80 piston rod, the inner end of this box terminating substantially flush with the inner wall of the cylinder head, a plurality of nozzles mounted in said box and having discharge orifices directed away from said piston rod, and an oil passage in the box for supplying oil to each nozzle.
6. In an internal combustion engine, the 85 combination of a cylinder, a piston in the cylinder, a head in the cylinder having a 90 passage therethrough, a piston rod connected to the piston and movable in the passage, a box in the passage fitting the piston rod, a plurality of nozzles mounted in the 95 box and extending into the cylinder in the space between the cylinder head and the piston, these nozzles having discharge orifices directed away from the piston rod, and an oil passage in the box communicating with each nozzle.
7. In an internal combustion engine, the 100 combination of a cylinder, a head in the cylinder having a passage formed through it, a piston in the cylinder, a piston rod connected to the piston and movable in the 105 passage, a box in the passage having a portion fitting the piston rod and another portion of enlarged diameter, packing in the latter portion of the box fitting the piston rod, a gland for holding the packing in place, a plurality of nozzles mounted in one 110 end of the box and having radially directed discharge orifices, and oil passages in the box communicating with the nozzles.
8. In an internal combustion engine, the 115 combination of a cylinder having an integrally formed head provided with a passage communicating with the cylinder, a continuous water jacket enclosing the cylinder and head, a piston in the cylinder mounted 120 on a rod extending through the passage, a box in the passage fitting the piston rod the inner end of this box terminating substantially flush with the inner wall of the cylinder head, a plurality of nozzles having orifices discharging outwardly into said cylinder, and an oil supply passage for each 125 nozzle through the box.
9. In an internal combustion engine, the 130 combination of a cylinder, a head in the

- cylinder having a passage therethrough, a piston in the cylinder; a piston rod on which the piston is mounted, extending through the passage, a box in the passage fitting the piston rod, one end of this box lying flush with the inner face of the head, a plurality of nozzles mounted in the flush end of the box and extending into the cylinder, these nozzles having outwardly directed discharge orifices, a plurality of inlet openings, one for each nozzle, located in the other end of the box, and an oil passage in the box extending between each inlet opening and the nozzle associated therewith.
10. A box for encasing the packing for the piston rod of a double acting internal combustion engine, containing a plurality of oil passages therethrough, and a nozzle for each passage having an orifice discharging into the cylinder.
15. 11. A box for encasing the packing for

the piston rod of a double acting internal combustion engine, containing a plurality of oil passages, each passage having a discharge orifice directed away from the piston rod, the box having an enlarged rim at the end opposite to that in which the discharge orifices are located, this rim having inlets through which the oil is introduced into the passages.

20. 12. A box for encasing the packing for the piston rod of a double acting internal combustion engine containing a plurality of oil passages and a plurality of nozzles mounted in the box, each nozzle communicating with one of said passages and the nozzles being adapted to lie beyond the end of the box within the cylinder.

25. 30. 35. In testimony whereof I affix my signature.

LAWRENCE Y. SPEAR.
